LOAD HANDLING APPARATUS

Harold E. Mescher, Rivera, and Sven O. Rosensson, Alhambra, Calif., assignors to Pacific Scientific Company, San Francisco, Calif., a corporation of California

Filed Feb. 18, 1959, Ser. No. 794,050

8 Claims. (Cl. 294—110)

This invention relates generally, to apparatus for handling loads or equipment which are inaccessible to direct personal contact due, for example, to the high temperature of the load, or picking up or placing the same in areas difficult to access by operating personnel, or where the load consists of containers of dangerous chemicals, etc., and the invention relates, more specifically, to a novel load handling apparatus that can be suitably carried by a building crane and/or lifting chain and cable mechanism and which apparatus is suitable, for example, for lifting material or parts to be heat treated into a high temperature furnace and thereafter for moving the material or parts into a quenching tank. Such load handling apparatus embodies novel coupling means whereby the load may be coupled to the building crane lifting cable and uncoupled therefrom without the necessity of using manual contact with the load.

In the heat treatment of materials and particularly the heat treatment of large members such as airplane or missile parts it is often necessary to pick up the material or members and raise the same into a heat treating furnace wherein the material is heated to a desired high temperature and thereafter the material or members are lowered into a quenching tank, which operations must be performed without operating personnel being present in the immediate vicinity of the material or members being treated due to high temperatures existing in and about the furnace. Also, in the handling of dangerous chemicals it is desirable that operating personnel do not get too close to the material being handled.

It is therefore the principal object of the present invention to provide a novel load handling apparatus that is capable of receiving material or members to be processed or handled in a suitable convenient place whereupon the apparatus is adapted to be picked up by an overhead crane and/or lifting chain and cable mechanism and moved to a point such as into a furnace where the material or members are to be used or operated upon and which may be moved through a series of desired operations without the material or members being directly handled by personnel, the novel load handling apparatus being designed so as to withstand high temperatures, injurious chemicals, and other difficult environmental uses.

A feature of the present invention is to provide a novel coupling member that is adapted to automatically couple a load to a cable or chain of a lifting apparatus such as a building crane when desired and which is also capable of automatically disconnecting the load from the cable or chain as desired, whereby loads may be handled conveniently without personnel coming in contact therewith.

Still another feature of the present invention is to provide a novel load handling apparatus of the above character having spider members for carrying a load, together with suspension rods and adjustable hold down

2

means for retaining the load in a desired position upon the load handling apparatus.

These and other features and advantages of the present invention will become more apparent after a perusal 5 of the following specification taken in connection with the accompanying drawings wherein,

Fig. 1 is a perspective view of the novel load handling apparatus of this invention,

Fig. 2 is a partial transverse sectional view of the 10 upper spider and coupling member shown in Fig. 1,

Fig. 3 is a reduced fragmentary view taken along the line 3—3 of Fig. 2 looking in the direction of the arrows,

Fig. 4 is an enlarged fragmentary view partly in section 15 illustrating the manner of inserting the cable carrying coupling pin into or out of the upper spider of the apparatus,

Fig. 5 is a view similar to Fig. 4 taken along line 20 5—5 of Fig. 3 and illustrates the initial movement of the coupling pin preparatory to removing the same from the coupling member, and

Fig. 6 shows the coupling pin actually being withdrawn from the coupling member.

Referring now to the drawings, Fig. 1 illustrates the 25 novel load handling apparatus as a whole, said apparatus comprising a coupling pin 1 adapted to be attached at its upper end to the cable or chain of any suitable supporting and carrying means such as a building crane and/or a lifting chain and cable mechanism. The pin 1 hangs downward from the supporting cable or chain and is adapted to enter the central opening 2 in a hollow hub 3 of a supporting member illustrated as spider 4 which may be termed the upper spider of the load handling apparatus. The spider 4 has a plurality of radially extending arms 5 provided with apertures 6 at varying radial distances to which may be removably connected 30 depending supporting rods 7 as by pins or bolts. The number of rods 7 employed and the radial position of the same will depend upon the material or members carried. In Fig. 1 three of these rods are shown and have their lower ends connected to a lower spider 8 having a central apertured hub 28, which spider is illustrated as of somewhat smaller diameter than the upper spider 4 for certain installations as where the lower spider is 35 adapted to be inserted in a quenching tank as when quenching material carried by the spider 8. This quenching tank may be of the type disclosed and claimed in pending application Serial No. 794,029, filed February 18, 1959, for quenching apparatus in which one of the 40 present applicants, Harold E. Mescher, is a joint applicant both of which applications are owned by a common assignee. In such case the upper spider 4 is adapted to have the outer ends of its arms 5 rest upon the load ring of the quenching tank. Since the apertures 6 are 45 distributed radially along the arms 5 of the spiders, the rods 7 may be adjusted radially outward or inward depending upon the size of the load or member to be quenched. A hold down assembly, comprising a hub 50 9 and radial arms 10 adjustable as to length is shown positioned between the two spiders 4 and 8 for retaining the work or part down upon the spider 8 in use, the outer ends of the arms 10 being bifurcated at 11 for receiving pins insertable into any one of a series of 55 vertical apertures 12 in the rods 7.

The lower end of the coupling pin 1 is provided with an enlarged conical projection or end portion 13 that in descending through aperture 2 is adapted to engage and actuate a pair of opposed substantially C-shaped holding bars or members 14 downwardly and outwardly to accommodate the pin 1, see especially Fig. 3, which bars are fixedly carried by bell crank levers 15 pivoted as 60 65 70 75 80 85 90 95

by pins 16 upon the spider 4. With the coupling pin 1 fully inserted into the spider 4 as shown in Fig. 2 preparatory to lifting the spider and the load, the substantially opposed holding bars 14 engage the lower portion of the coupling pin 1 directly behind a shoulder 17 provided by the conical end portion 13. Since the upper portion of conical end portion 13 is somewhat larger than the pin 1 the step or shoulder 17 is provided for engaging the holding bars so that these bars are pressed upwardly and against the bottom of the spider hub 3 during the lifting of the spider and its load thus stressing bars 14 substantially in shear enabling the apparatus to handle relatively heavy loads with ease. It will be noted that the pivotal pins 16 do not carry any of the load but that the load is transmitted from the shoulder 17 through the holding bars 14 directly in shear to the hub 3, thereby providing an extremely rugged support for the spider and its load and one that is unaffected by high temperatures such as obtain in furnaces.

Fig. 4 shows the conical end portion 13 of the pin 1 as it enters or leaves the spider 4. It will be noted as the pin 1 is lowered, the conical end portion 13 will strike the opposed semi-cylindrical edges of the opposed holding bars 14 and will swing these bars downwardly about their pivots 16 sufficiently to enable the conical portion to pass through the substantial cylindrical opening provided between these bars whereupon the overhanging weighted portions 14' of these bars will serve to swing the bars inwardly and engage the pin 1 directly behind the shoulder 17 as shown in Fig. 2 so that the cable may then be raised effecting the lifting of the load and the movement of the same by the crane to any desired position such as inside a furnace or effecting the lowering of the load as when it is desired to lower the same into a quenching tank or pit.

When it is desired to uncouple the coupling pin 1 from the spider 4 and the load carried thereby, the crane operator will lower the load supporting spider 8 down upon a suitable support. He will then continue to lower the cable slightly as shown by the arrow in Fig. 5 of the drawings so that the pin 1 continues to move downwardly within the hollow hub 3 until a lower beveled shoulder 19 of a cylindrical boss 20 formed on the pin 1 strikes the semi-cylindrical edges of the opposed holding bars 14 and depresses these bars as shown in Fig. 5 thereby turning the same about their pivots 16. The upper arms 21 of bell crank levers 15 have outer curved ends that normally abut curved surfaces 22 of angled shaped locking levers 23 which are pivoted upon the spider 4 as by pivoted pins 24. These locking levers 23 are formed with locking shoulders or recesses 25 at the end of the curved surfaces 22 so that when the holding bars have been turned sufficiently about their pivotal pins 16 by the downward movement of coupling pin 1, the upper arms 21 of bell crank levers 15 will engage the locking recesses 25 due to the tendency of the levers 23 to fall radially inwardly toward the center of the spider, as illustrated in Fig. 5. With the bell crank arms 21 thusly engaged, the locking recesses 25 prevent levers 15 from turning under the influence of the overhanging weighted portions 14' of the holding bars so that these holding bars are held substantially in their positions as shown in Fig. 5, whereupon the coupling pin 1 can be raised as shown by the arrows in Fig. 6 allowing the shoulder 17 to pass the cylindrical opposed edges of the holding bars 16.

Further upward movement of the coupling pin 1 will cause the upper beveled shoulder 26 of boss 20 to strike the inner ends of angled locking levers 23, thereby turning these levers radially outward somewhat disengaging arms 21 from locking recesses 25 and enabling the weighted portions 14' to turn bell crank levers 15 so that the ends of arms 21 again engage and slide over the curved surfaces 22 of the locking levers so that as

pin 1 moves outwardly, the bell crank levers 15 will turn inwardly behind the conical end portion 13 of the pin 1 and again into the position shown in Fig. 4 whereby the pin 1 is free to be removed completely from the spider. The holding bars 14 and the locking bars 23 are thus again positioned preparatory to reinserting the pin 1 into the hub of the spider for another lifting and handling operation.

Thus it will be seen that, by merely controlling the position of pin 1 in its up-and-down motion, the crane operator by remote control is able to couple and uncouple the pin 1 with respect to the spider 4, as desired, and without the necessity of an operator manually coupling or uncoupling the pin 1 of the spider, so that should the work or treated member 27 carried by the lower spider 8 be in a heated condition and hence unapproachable by personnel, or should this member contain hot acid, for example, the same can be picked up, moved and again lowered to any position desired without any danger to operating personnel. It will be noted that the novel load handling apparatus of this invention is of simple construction using sturdy, rugged parts which can withstand high temperatures, acids, etc., without injury so that the same has a long life and is reliable in use. Since the holding bars 14 carry the load directly in shear, these bars are not deformed by high temperatures in use.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. Load handling apparatus comprising a load supporting member, said member having a hub provided with an opening therethrough, holding means pivoted on said member for projecting into said hub opening, a coupling pin vertically movable into and out of co-operative engagement with said hub opening and having a projection thereon engageable with said supporting member holding means, said supporting member holding means being caused to turn about its pivotal support on said member by vertical movement of said coupling pin projection with respect thereto, said holding means acting to engage said pin projection and said hub in shear and effect the firm coupling of said pin to said supporting member for raising and lowering the same.

2. A load handling apparatus as claimed in claim 1 wherein said holding means comprises holding bars pivoted upon said supporting member for engaging said coupling pin projection to effect the raising of said supporting member and its load, and locking levers pivoted on said supporting member for holding said locking bars in disengaged position, said coupling pin having a second projection thereon for engaging said holding bars and said locking levers to effect the release of said coupling pin from said supporting member.

3. Load handling apparatus as defined in claim 1 wherein supporting rods are removably attached to said supporting member for supporting the load, a second supporting member carried by said rods, and hold down means adjustably attached to said supporting rods for retaining work in fixed position upon said second supporting member in use.

4. In apparatus of the character described, a coupling device comprising a coupling pin and an apertured hub member for receiving said pin into the aperture thereof through vertical movements of the latter, said pin being completely removable from said hub member, said member having holding bars pivoted thereon and said coupling pin having a stop projection for engaging said holding bars for turning the same into abutting relation both to

said stop projection and to said hub member for supporting said holding bars and said member.

5. Apparatus as defined in claim 4 wherein locking levers are pivoted on said member and actuated by movement of said coupling pin for engaging said holding bars to hold the same out of engagement with said stop projection to thereby enable the disconnection of said coupling pin from said member.

6. In a load handling device, a coupling of the character described comprising, an apertured supporting member, a coupling pin adapted to be passed into and out of the aperture of said supporting member, pivoted holding bars carried by said supporting member, said coupling pin having an enlarged conical end portion for engaging and actuating said holding bars to effect the engagement of said pin with said bars for supporting said member therefrom, and locking levers carried by said supporting member for engaging said holding bars, said coupling pin having a boss thereon for engaging said holding bars and said locking levers in succession through vertical movement of said coupling pin to effect the disconnection of said coupling pin from said member.

7. A load handling device as defined in claim 6, wherein said coupling pin engages said holding bars in

shear and said holding bars engage said supporting member in shear, whereby said load handling device is capable of carrying relatively heavy loads under adverse conditions without any eccentric forces being exerted upon the coupling pin.

8. In apparatus of the character described, a coupling member comprising, a hollow hub structure, a coupling pin having a conical end portion adapted to be passed into and out of said hollow hub structure, holding bars pivoted upon said hub structure and engageable by said coupling pin conical end portion for supporting said hub structure from said pin, locking levers pivoted upon said hub structure, and cam means on said coupling pin and spaced from its conical end portion for actuating said locking levers to effect the locking of said holding bars in disengaged position with respect to said coupling pin conical end portion, whereby the latter may be completely withdrawn from the hollow hub of said hub structure.
